UNITED STATES PATENT OFFICE

2,550,290

CATALYTIC CRACKING OF HYDROCARBONS

Harry Louis Pelzer, Steger, Ill., and Kenneth Merle Watson, Madison, Wis., assignors to Sinclair Refining Company, New York, N. Y., a corporation of Maine

Application June 27, 1947, Serial No. 757,651

2 Claims. (Cl. 196—52)

1

This invention relates to the pyrolytic cracking of hydrocarbons and, more particularly, to such processes wherein the hydrocarbons are cracked in the presence of a solid catalyst.

The invention provides an improved catalytic cracking process especially useful in the cracking of heavier hydrocarbon distillates, gas oil for instance, to produce a lighter, lower boiling fraction within the motor fuel, or gasoline, range.

In a once-through cracking operation, even under most advantageous conditions, only a portion of the charging stock is cracked to the desired product. In addition to constituents within the desired boiling range, the effluent from the cracking reaction zone contains a relatively large amount of higher boiling hydrocarbons and it is customary to separate the lighter from the heavier hydrocarbon constituents by fractional condensation.

In order to increase the yield of the desired product from a given amount of charging stock, it has been proposed to return the heavier hydrocarbon fraction to the reaction zone for further cracking in admixture with the fresh charging stock.

Unfortunately, the heavier fractions separated from the effluent from the cracking zone, commonly designated recycle stock, contains constituents having cracking characteristics, substantially different from those of the fresh virgin charge oil. Usually, the recycle stock is more resistant to cracking, or further cracking, than the fresh charge oil.

If these more highly refractory insufficiently cracked constituents of the effluent vapors are recharged to the cracking zone, together with the virgin gas oil, for instance, in which conditions optimum for the cracking of the gas oil are maintained, they will undergo little or no decomposition and will accumulate in the system, and if cracking conditions optimum for their cracking are maintained in the cracking zone, the gas oil will be overcracked.

In accordance with our present invention, these and other objectionable conditions are avoided in a catalytic cracking unit by separately cracking the virgin charge oil and the recycle stock in separate reactors. Advantageously, the constituents of the effluent vapors from the cracking of the virgin stock which are heavier than the desired product are fractionated to form a heavier and a lighter recycle stock and these fractions are subjected to different cracking conditions as by injecting them into different zones of the second reactor. Catalyst which has been used in

2

the cracking of the virgin charge stock in the first reactor is, with advantage, passed to the second reactor wherein cracking conditions usually more severe than those to which the virgin charge oil is subjected are maintained.

The invention is particularly applicable to processes of the fluid catalyst type, but is also applicable to processes involving moving beds of non-fluidized catalyst in which hot, freshly regenerated catalyst is supplied to the upper end of the bed and spent catalyst is withdrawn from the lower end of the bed for regeneration.

The invention will be further described and illustrated with reference to the accompanying drawing which represents conventionally and diagrammatically a flow diagram of the fluid catalyst cracking operation embodying my invention.

In the operation shown in the drawing, a virgin charge oil, gas oil for instance, is passed to the system through line 1, is admixed with catalyst passing through line 2 from regenerator 3 to form a suspension which is passed upwardly into the lower end of reactor 4. Products of the cracking reaction pass from reactor 4 through line 5 to the fractionator 6 in which a lighter fraction containing the desired product is separated and passes as a vapor from the upper end of the fractionator through line 7. A heavier fraction is withdrawn from the lower end of the fractionator through line 8 and an intermediate fraction withdrawn as a side stream through line 9.

Catalyst which has been used in the reactor 4, passes therefrom through line 10 into line 9 and is caught up in suspension in the intermediate fraction and carried upwardly into the reactor 11. The heavier fraction, withdrawn from the lower end of the fractionator, is passed through line 8 into an intermediate zone of the reactor 11.

Spent catalyst is withdrawn from reactor 11 through line 12 and passed to regenerator 3 wherein the catalyst is regenerated and returned to reactor 4 for further contact with fresh virgin charge oil. Hydrocarbon vapors, withdrawn from reactor 11, pass through line 13 to fractionator 14 from which the lighter constituents are withdrawn through line 15 and the heavier condensate withdrawn through line 16.

By the operation shown, a higher gasoline yield and a lower over-all coke formation is attained than is attained in known equivalent, recycle, or once-through operations yielding higher than 40% of the desired product. The present process will produce yields within the range of 40 to 90%.

The invention contemplates known means for conveying the catalyst, regenerating the catalyst and effecting contact between the catalyst and the respective gases and vapors and need not here be described in detail. In general, the regeneration may be effected by passing air in contact with the spent catalyst whereby carbonaceous deposit formed thereon during the cracking operation is burned. In a fluid cracking operation, the catalyst is conveyed in fluid suspension in a suitable gaseous medium and in the so-called moving bed process of the T. C. C. type, conventional conveying means may be employed.

The catalyst used may be the type conventionally used in cracking processes. In the application of the present invention to fluid catalyst processes, the catalyst used may, for instance, be a silica-alumina type catalyst in finely divided or powdered form. The reaction conditions may, likewise, be those conventionally used in operations of this general type and, as understood by the art, the optimum temperatures and pressures will depend primarily upon the type of feed stock used, the particular catalyst employed and the depth of cracking required.

In cracking gas oil, for instance, the reaction temperature may, with advantage, be within the range of about 800 to 1,000° F. and the pressure at the top of the reactor within the range of about 5 to 25 pounds per square inch. The regeneration temperature is, with advantage, within the range of about 950 to 1,200° F., heat for the reaction being supplied, in large measure at least, by the hot regenerated catalyst.

Usually, the charge oil will be preheated and vaporized, or partially vaporized, before being mixed with the catalyst from the regenerator. The recycle stock from fractionator 6 may, likewise, be preheated and vaporized, or partially vaporized, before being passed to the reactor 11.

Cracking conditions maintained in the second reactor will normally be more severe than those maintained in the first reactor, optimum conditions depending upon the characteristics of the recycle stock. The more refractory intermediate fractions passing to the lower end of the second reactor will ordinarily be subject to more severe cracking conditions than the fraction of recycle stock passed to the intermediate zone of the second reactor.

The amount of recycle stock passed to the

second reactor will ordinarily be substantially less than the amount of virgin charge oil passed to the first reactor. The amount of catalyst used for each of the reactors will ordinarily be the same. Consequently, the catalyst-oil ratio in the second reactor may be substantially greater than that in the first reactor, resulting in more severe cracking conditions in the second reactor.

Where higher temperatures are desired in the second reactor than in the first reactor, heat may be supplied to the second reactor by known means, for instance, by strongly preheating the recycle stock passing thereto from the fractionator 6.

We claim:

1. In a process for the catalytic cracking of hydrocarbons wherein the hydrocarbons are passed in contact with a cracking catalyst in a conversion chamber and the effluent vapors therefrom are fractionated to form an insufficiently cracked fraction heavier than the desired fraction and which is subjected to further cracking, the steps of separating the insufficiently cracked fraction into a heavier and a lighter fraction, introducing the lighter fraction into one end of a separate elongated conversion chamber, passing it therethrough in contact with hot catalyst discarded from the primary conversion chamber, introducing the heavier fraction into the separate conversion chamber at an intermediate zone into contact with said hot catalyst and withdrawing cracked vapors from the opposite end of the separate conversion chamber.
2. The process of claim 1 in which the catalyst-oil ratio in the separate conversion chamber is in excess of that in the first conversion chamber.

HARRY LOUIS PELZER.
